BRACKET FOR GRINDING WHEELS

Bogosia Strezoff, Minneapolis, Minn.

Application January 22, 1942, Serial No. 427,741

2 Claims. (Cl. 51—125)

This invention relates to sharpening devices. One of the objects of my invention is to provide a device for sharpening instruments such as knives and scissors, wherein a conventional rotary grinder or sharpener is utilized in conjunction with a specially devised supporting bracket for holding the grinder and also for supporting the work holder.

Another object of the invention is to provide a supporting bracket for a conventional grinder with an adjustable work holder on the bracket wherein the grinder includes an attaching clamp adapted to secure it to a bracket and hold the adjustable work holder in any one of a number of various adjusted positions.

A further object of the invention is to provide a bracket with a work holder thereon and a grinder detachably securable to the bracket wherein the work holder is adjustable toward and away from the bracket as well as being adjustable angularly thereto.

These and other objects and advantages of the invention will more fully appear from the following description made in connection with the accompanying drawing, wherein like reference characters refer to the same parts throughout the views, and, in which:

Fig. 1 is a plan view; and

Fig. 2 is a side elevation.

In the drawing there is shown a portion of a table shelf or other stationary support 3. A bracket 12 is provided with an inner end 4 which is adapted to overlie the support 3. The central portion of the bracket 12 is provided with a cut-out 5 and the tongue 6 formed by said cut-out is bent downwardly and its portion 6a bent inwardly parallel to the bracket portion 4 in spaced relation thereto. The bracket portion 6a has a clamping bolt 7 threaded therethrough with a swiveled end member 8 to permit the bracket to be tightly secured to the support 3, as shown.

A pair of arms 9 extend outwardly beside the central cut-out 5 and are connected at their outer or left-hand ends by a horizontal cross member 10. The horizontal cross member 10 at its outer or left-hand edge is provided with an upturned portion 11 having a series of vertically disposed teeth 12 formed on its outer face. Positioned centrally of the cross member 10 is a vertically disposed threaded post 13 upon which a sleeve 14 is threaded, said sleeve 14 being vertically adjustable by rotation thereof on the threaded post 13. Mounted on the top of the vertical sleeve 14 is a horizontally disposed split sleeve 15 which threadedly receives an externally

threaded member 16 having connected thereto a work holder 17. The split sleeve 15 has a pair of upwardly extending lips 18 carrying a clamping screw 19 adapted to tighten said split sleeve 15 about the externally threaded member 16.

There is shown a conventional grinding tool T having a body 20 rotatably supporting a grinding wheel 21 driven by suitable gearing from a rotary crank 22. The grinding tool body 20 has a pair of substantially vertically disposed lugs 23 thereon whose right-hand vertical edges are adapted to engage the teeth 12 on the upstanding flange 11 of the bracket cross member 10. An angular tongue 24 extends rearwardly or to the right from the grinding tool body 20 and the upstanding portion of said tongue 24 threadedly supports a clamping screw 25 having a clamping element 26 pivoted on its left-hand or inner end. When the grinding tool T is placed in the position shown with the lugs 23 engaging the teeth 12 on the bracket portion 11 and the clamping screw 25 is screwed to the left the clamping element 26 on said screw 25 will engage the vertically disposed internally threaded sleeve 14 on the externally threaded member 13, and the lugs 23 will be brought into firm engagement with the teeth 12 on the bracket cross member portion 11. This clamping action not only supports the grinding tool with its wheel 21 in proper relative position to the work holder 17, but it clamps the relatively movable threaded members 13 and 14 against movement.

In the position illustrated the work holder 17 is in an elevated position relative to the grind stone 21 and it has a scissors blade 27 held therein by the jaws of the holder and by a tightening screw 28 which causes firm engagement of the work holder 17 on the scissors blade 27. When the work holder is tilted to the desired angle for the grinding of scissors blades the screw 19 on the split sleeve 15 is tightened to maintain said angular position. When sharpening of a knife blade is desired the clamping screw 25 is loosened to permit the vertically disposed sleeve 14 to be screwed down on the externally threaded member 13 thus lowering the work holder 17. When the holder 17 has been lowered to the desired position the clamping screw 25 is again tightened against the sleeve 14. The split sleeve 15 can be loosened by manipulation of screw 19 so that the work holder 17 can be oscillated about its longitudinal axis to bring alternate sides of the edge of a knife blade into engagement with the grind stone 21.

From the foregoing description it will be seen

that I have provided a sharpening device which utilizes a conventional type of grinding tool and a bracket to which the grinding tool can be detachably secured. When secured to the bracket the grinding tool can be utilized to sharpen instruments such as scissors and knife blades and said grinding tool can be quickly detached from the bracket so that it may be utilized independently for any other uses to which it might be put.

It will, of course, be understood that various changes may be made in the form, details, arrangement and proportions of the various parts without departing from the scope of my invention.

What is claimed is:

1. In a device of the class described, a bracket having an abutment thereon to engage the frame of a tool such as a hand grinder having a screw

clamp thereon, a threaded post on said bracket adjacent said abutment opposite to that side of said abutment engaged by said grinder frame, a work supporting sleeve threaded on said post and engageable by the screw of said clamp to clamp said grinder to said bracket to lock said sleeve against rotation on said post.

2. The structure in claim 1 and said sleeve having a split collar thereon having an internal thread and lying at right-angles to the axis of said collar, a work clamping device having a portion threaded into said split collar, ears extending from said collar, and means for releasably drawing said ears together to tighten said split sleeve on said threaded work clamping device portion.

BOGOIA STREZOFF.
